UNITED STATES PATENT OFFICE.

HOWARD DE WOLFE SAWYER, OF REVERE, MASSACHUSETTS, ASSIGNOR, BY DIRECT AND MESNE ASSIGNMENTS, TO WILLIAM H. KIMBALL, OF BOSTON, MASSACHUSETTS, AS TRUSTEE FOR WILLIAM H. KIMBALL, OF BOSTON, MASSACHUSETTS, FIFTEEN THIRTY-SECONDS; HOWARD DE W. SAWYER, OF REVERE, MASSACHUSETTS, FIFTEEN THIRTY-SECONDS; AND HERBERT B. NEWTON, OF BROOKLINE, MASSACHUSETTS, TWO THIRTY-SECONDS.

FIRE-BOX FOR LOCOMOTIVE-ENGINES.

1,275,763.

Specification of Letters Patent. Patented Aug. 13, 1918.

Application filed January 13, 1911. Serial No. 602,432.

To all whom it may concern:

Be it known that I, HOWARD DE WOLFE SAWYER, of Revere, in the county of Suffolk and State of Massachusetts, have invented 5 certain new and useful Improvements in Fire-Boxes for Locomotive-Engines, of which the following is a specification.

The object of this invention is to provide for locomotive and other boilers an improved construction of fire-box, embodying 10 in a practical form a new arrangement of tubular, water-containing grate-bars with a system of downward draft between such bars, whereby the gases evolved and all volatile products of combustion are consumed 15 as fuel, instead of contaminating the air, endangering adjacent property and starting forest fires in the regions through which the locomotives pass. The general construction 20 and certain novel features thereof are hereinafter described, and the present invention especially referred to in the appended claims.

A special feature of this improvement is the peculiar depending barrier at the inner 25 end of the fuel chamber, supported by the grate tubes and their upward extensions to the crown sheet and additionally by an arched plate fixed to said sheet, such barrier enforcing the draft downwardly between 30 the tubes of the grate into the gas combustion chamber beneath it and behind said barrier.

In the accompanying drawings Figure 1. represents a longitudinal central section 35 taken vertically through my improved fire-box; Fig. 2. a horizontal section thereof, on the line 2—2 of Fig. 1. and Fig. 3. a transverse section, taken on the broken line 3—3, Fig. 1. looking to the left. Fig. 4 represents 40 a detail.

The boiler here illustrated has hollow, water-containing walls 6 connecting with the steam space 7 above the crown sheet 8 and horizontal flues 9. The fire-box comprises the fuel chamber 10, above the fuel 45 supporting grate, and the gas combustion chamber 11 beneath and beyond such grate.

As shown in Figs. 1, 2 and 3 the tubular bars of the grate 12 all lie in the same plane 50 and are alternately of different lengths, so that half of the series extend at the inner

end considerably beyond the others. Each tube there has an upward extension 13 with coupling 14, and, at top, a union or other threaded joint connecting it, through an arched reinforcing plate 23, to the crown sheet 8, thus providing continuous water currents between the water wall 6 and steam space 7, and affording substantial support to the barrier. 60

With the tubes thus arranged and in the space inclosed by them, between the side walls of the boiler, I build up, of fire bricks of suitable size and shape, the barrier 15, which serves to deflect downwardly the draft entering through the fuel door 16, and carry the caloric current between the grate tubes, as stated. The fire bricks are readily inserted edgewise through the wide spaces between the upright extension tubes 13, see 70 Figs. 2 and 3, and then properly placed upon and above the alternate projecting tubes 12 and any crevices filled with cement. Such a barrier is of great durability, holds the heat for many hours and leaves the tubes 13, in 75 front and back of it, exposed at all times to the full intensity of the caloric current. Furthermore it requires no cutting away of the water walls of the fire-box since its ends do not communicate therewith. 80

To facilitate connecting the upright tubes 13 to the crown sheet 8, especially at the edges of the barrier 15, I have devised the tubular manifolds 17, conforming marginally to the general sweep of the fire-box 85 where its side walls merge in the crown sheet. The upper end of this manifold is enlarged and connected by a union or other joint, and there are two or more depending arms, internally threaded at bottom, to receive the tips of the respective upright tubes 13. Fig. 3, shows in full lines three of these tubes connecting with one manifold and two with the other, while the dotted lines denote respectively two and three such uprights connecting with the manifolds of the opposite face of the barrier and coupled to the alternate grate tubes. 95

The detail drawing Fig. 4 shows a sectional illustration of this construction. 100

In view of the great heat of the down draft current I provide my fire-box with a

substantial fire brick bottom 18, the walls sloping inwardly to a central door 19, hinged for discharge of ashes and furnished with a suitable fastening catch. The bricks 5 are held in position by inverted T-shaped bars 22, fixed to the metal bottom beneath them, as indicated in the cross-section Fig. 3.

A limited amount of fresh air may be admitted to the fuel and combustion chambers by means of hollow stay bolts or tubes 21, which I thread externally and introduce through the water walls 6, and terminally upset them, as indicated in Figs. 1, 2 and 3. I however make no claim to this feature.

15 I claim as my invention:

1. In combination with a firebox having water walls at its front, sides and top, a fuel grate consisting of water tubes lying in substantially the same plane and close to each other, certain of which are of greater length than the remaining tubes, two series of upright water tubes coupled to the grate tubes and arranged in planes which are parallel from their upper to their extreme lower ends, said series extending transversely completely across the fire box, the upright tubes being connected to the crown sheet and the grate tubes to the front water wall, and a solid barrier of independent fire brick

filling the space between the series of upright tubes and having a flat bottom or base resting on and supported by the extended parts of the longer tubes of the fire grate.

2. In a down draft locomotive fire-box having tubular grate bars and upright tubular extensions thereof, for water circulation as described, the combination therewith of the tubular manifold 17, adapted for water communication through the crown sheet and provided with threaded depending arms to receive said extensions, substantially as set forth.

3. In a down draft locomotive fire-box a single tubular fuel grate and upright tubular extensions thereof and a transverse barrier connected to and depending from the crown sheet, serving to deflect the caloric current between the grate bars, in combination with a fire brick heat reflecting bottom arranged to deflect the heat beyond the barrier.

In testimony whereof I have affixed my signature in presence of two witnesses.

HOWARD DE WOLF SAWYER.
